UNITED STATES PATENT OFFICE.

AUGUST A. WIMMERS, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed February 13, 1920. Serial No. 358,557.

To all whom it may concern:

Be it known that I, AUGUST A. WIMMERS, a citizen of the United States, residing at Dayton, in the county of Montgomery and 5 State of Ohio, have invented certain new and useful Improvements in Autographic Registers, of which the following is a specification, reference being had therein to the accompanying drawing.

10 This invention relates to autographic registers, and has for its particular object to provide an improved autographic register which will be free in its use of certain difficulties which are common to registers of 15 the type to which these improvements relate.

A further difficulty experienced with the paper feeding mechanism of autographic registers of this type consists in tearing of 20 the paper web by the feeding devices, the common practice being to use paper put up in rolls and having perforated edges which are positively engaged by feeding devices to draw the paper from the roll or rolls 25 and advance the same over the writing tablet a predetermined distance at each operation of the register, except when the paper tears or fails for other reasons to function properly in its movement through 30 the feeding mechanism.

As stated, the present invention provides an autographic register having improved paper feeding traveling means which acts on the body of the roll or rolls of paper to 35 pay the paper off and enable it being fed through the machine without risk of being torn by the feeding devices which act on the unrolled web or webs.

Other advantages of the improved register 40 relate to details of the mechanism,—simplicity and cheapness of construction, and general dependability of arrangement and organized operation having been provided for in all parts of the mechanism.

45 In the accompanying drawings,

Fig. 1 is a vertical longitudinal section of an autographic register embodying the present invention;

50 Fig. 2 is a plan view of the register shown in Fig. 1, with the top cover plates removed from the casing;

55 Fig. 3 is a detail view of a type of paper feeding mechanism used on well known types of autographic registers and used in the construction here shown in connection

with the improved paper feeding mechanism of the present invention;

Fig. 4 is a detail in cross section showing features of the paper feeding mechanism

60 Figs. 5 and 6 are detail views, respectively, of the writing tablet plate and improved casing cover plate.

The invention is here shown in a preferred form of construction, but it will be understood that various modifications may 65 be made in the mechanical details and arrangement without impairing the general effectiveness of the mechanism in accomplishing the purposes of the invention and without departing from its underlying 70 principles.

As shown in the drawings the register cabinet 1 is rectangular-shaped in cross section, and is provided at one end thereof with a hinged door 2, the top of the cabinet 75 being covered by plates 3, 4 and 5, the plates 4 and 5 respectively being the writing tablet and tablet cover plate, the latter having a large rectangular-shaped aperture 7 therein to uncover the work surface of the tablet plate 4.

Within the register cabinet, as here shown, are two paper roll supporting shafts 8, mounted to have free vertical movement between guides 9 which are secured to the 80 opposite side walls of the cabinet, there being two of the guides for each shaft 8, one for each end thereof. Cooperating with each shaft 8 and acting to exert pressure thereon in the downward direction are two 85 opposite arms 10 which are pivotally mounted on transverse fixed rods 11 having their ends supported in bearings provided in the opposite sides of the register cabinet. Springs 12 coiled about the shafts and having one end anchored to the cabinet tend to 90 rotate the arms 10 in clockwise direction and thus to exert pressure on the shafts 8.

95 Each of the shafts 8, as here shown, has mounted thereon a roll of paper 13, having the outer end of the paper web released and drawn upwardly over paper guides 14, respectively, and thence over the writing tablet 4 into engagement with the paper feeding mechanism which will presently be described.

100 From the foregoing description of the paper roll mounting mechanism it will be seen that the paper rolls, with the gradually reduced size thereof as the registers are used, will be at all times forced to the limit of 110

their movement in the downward direction by the pressure exerted on the paper roll supporting shafts 8 by the arms 10. In this connection the improved paper feeding mechanism which is the feature of the present invention will now be described.

The improved register here shown is provided with geared paper feeding devices, consisting of a feed shaft 15 which is supported in the sides of the cabinet and extends transversely across the upper forward portion thereof. The shaft has paper-engaging devices secured thereto in the form of two opposite toothed disks or wheels 16, the teeth 17 being secured in the periphery of the disks and evenly spaced to engage equally spaced apertures in alignment therewith in the opposite edges of the paper webs. The shaft and paper feeding devices are operated by a crank 18 which is geared to the shaft by gears 19, 20 and 21, the gear 20 being an intermediate gear to provide for actuating the feed shaft in a forward direction with the operation of the operating handle in the same direction, reverse movement of the mechanism being prevented by an adjustable ratchet device 23.

The ratio of the gears 19 and 21 is such that the paper web will be advanced substantially the exact distance of one printed form or other measured portion of the web, upon each operation of the register, provision being made by mounting the intermediate gear 20 on a pivotally adjustable arm 22, to vary the gear ratios by interchanging either or both of the gears 19 with gears of different size, and thus to provide for printed forms of variable lengths.

With respect to the foregoing details of the paper feeding mechanism no novelty is claimed in the present invention, except as to their broad use in combination with the improved paper feeding traveling mechanism which will now be described.

Secured to the paper feed shaft 15, intermediate the toothed disks 16, is a toothed disk 24 which is traversed by an endless friction traveling element or belt 26, the belt having evenly spaced apertures 27 therein adapted to be engaged by the teeth 25 of the disk 24 to positively move the belt forward in its upper travel with the forward movement of the paper web. From the disk 24 the belt travels downwardly over a guide roller 28 extending transversely across the lower portion of the cabinet, thence in a horizontal plane to the rear of the cabinet where it passes over a roller 29 which is mounted in an adjustable bracket 30, whereby the tension of the belt may be regulated. In its forward travel from the roller 29 the belt passes under the paper rolls 13 having friction contact therewith, thence over guide rods 31, substantially parallel with its lower course under a guide roller 32, and upward-

ly over the feed disk 24, thus completing the endless path or course of its travel, the belt being in friction contact with the lower paper web as it passes over the disk.

The disk 24 including the thickness of the belt thereon is substantially equal in diameter to the disks 16. Thus the belt in its forward travel will cooperate with the usual paper feeding devices 16, by means of its friction contact with the paper rolls and with the paper web as it passes over the feeding devices, to more positively feed the paper forward the required distance at each operation of the register.

The belt acts to rotate the paper rolls the exact extent required to unwind therefrom the amount of paper required for the feed, and thus greatly reduces the pull exerted on the paper by the feeding devices 16, and accordingly minimizes the tendency of the teeth 17 to tear the paper and render the spacing of the paper out of alignment with the writing tablet. The contact of the belt with the paper web adjacent its tearing edge also aids materially in feeding the paper forward evenly and better supports the paper as the slips are torn off.

The plate 3 supported in guides 33 formed in the upper edges of the cabinet sides has a paper guide 6, notches 34, for the feeding pins, a notch 35 for the disks 24 and shoulders 36 to engage adjacent lugs 37 secured to the underside of the plate 5, to lock the plate in closed position; but this plate with its peculiarities and the paper guide 6 form no part of my invention, being the invention of Milton C. Stern, and the subject-matter of an application for a patent filed by him, July 2nd, 1920, Serial No. 393,489, and assigned to my assignee of this invention and application, The Egry Register Company.

The plate 5 is provided with a downwardly inclined forward edge 5^a which is immediately adjacent the inclined upper surface of the paper guide 6 and serves as a tearing edge for the paper slips, the paper web or webs 13^a, as here shown, passing between the edge 5^a and guide 6.

The writing tablet 4 is of an improved type, but no novelty is claimed in connection therewith in the present invention except that a clearance space 4^a is provided in the front edge thereof for the disk 24 and belt 26, clearance slots 4^b for the paper feeding disks 16, and supporting lugs 4^c adapted to fit in the notches 4^d in the upper edges of the cabinet to support the writing tablet, being also provided but not claimed in their detail arrangement as part of the present invention.

It will be understood from the foregoing detailed description and the illustrations of the drawings that when the cabinet is closed the plates 3, 4, 5 and the door 2 will be interlocked and that when the door 2 is opened,

the door being hinged at 2^a, the plate 3 may be partially or entirely withdrawn from the cabinet and thus release the cover plate 5 which may then be opened, the lid being 5 hinged at 5^a, to release the writing tablet 4. The writing tablet thus released may be lifted bodily from the cabinet and thus afford free access to the interior of the register.

10 Having particular reference to the improved paper feeding devices the principle of the invention, as here shown in one improved form, as far as I am aware is broadly new in this art and I desire to claim the invention broadly therefor, as defined and comprehended in the appended claims.

It will be observed that I have set forth and claimed herein a traveling means for operating the paper roll or rolls to pay off 20 the paper, the term traveling being used by me in the sense of mechanism which moves along in a line past the roll or rolls of paper, and engages them to unwind the paper.

In my copending application, filed Feb. 25 13, 1920, Serial No. 358,557, I have set forth and claimed my invention to accomplish this end in its broadest aspect or in a generic sense, as also in respect of a form of embodiment in which the mechanism for operating the rolls to unwind the paper is 30 in the form of rolls or disks which rotate about their center as distinguished from traveling along in a line under the rolls in the sense above pointed out.

35 I therefore wish to be understood, through the operation of this cross reference as generically claiming my said invention as well as claiming it in one specific form in my said other application, while in this present 40 application, I desire to be understood as claiming it in another form of embodiment.

Having thus fully described my invention, what I claim as new and desire to secure by Letters Patent, is:—

45 1. In paper feeding devices, the combination with a paper roll support, of paper feeding devices consisting of a shaft and oppositely toothed disks operable thereon and having means to positively engage 50 the paper web extended from said roll, a toothed disk mounted on said shaft intermediate the paper engaging disks and having traveling means cooperating therewith to form frictional engagement with the 55 paper web and cooperating with said opposite disks to draw the web from said roll.

60 2. In paper feeding devices, the combination, with a paper roll support, of paper feeding devices consisting of a shaft and oppositely toothed disks operable thereon and having means to positively engage the paper web extended from said roll, a toothed disk secured to said shaft intermediate the paper engaging disks, and an

endless belt in engagement with the paper web and traversing the intermediate disk and cooperating with said opposite disk to draw the paper web from said roll.

3. In paper feeding devices, the combination, with a paper roll support, of paper feeding devices consisting of a shaft and oppositely toothed disks operable thereon and having means to positively engage the paper web extended from said roll, a toothed 70 disk secured to said shaft intermediate the paper engaging disks, and an endless belt in engagement with and acting to rotate the paper roll thereby cooperating with said opposite disks to draw the paper web from 75 said roll.

4. An autographic register comprising a casing having an opening, a paper support below the opening, manually operated devices for drawing the paper over the support, a paper roll supporting shaft and an endless band paper pay off device adapted to engage a paper roll arranged upon the supporting shaft and to pay off the paper as it is drawn over the paper support. 85

5. An autographic register comprising a casing having an opening, a paper support below the opening, manually operated devices for drawing the paper over the support, a paper roll supporting axle, an endless paper pay off device adapted to engage a paper roll arranged upon the supporting axle to pay off the paper as it is drawn over the paper support, and means for varying the tension of the paper pay off device. 95

6. An autographic register comprising a casing having an opening, a paper support below the opening, manually operated devices for drawing the paper over the support, a paper roll supporting axle, an endless band paper pay off device to pay off the paper from the roll as it is drawn over the paper support, said supporting axle being movable with respect to the pay off device whereby to maintain contact of the paper roll with said pay off device. 100

7. An autographic register comprising a casing having an opening, a paper support below the opening, manually operated devices for drawing the paper over the support, a paper roll supporting axle and an endless band pay off device mounted to travel in a fixed path to pay off the paper from the roll as it is drawn over the paper support, said paper roll supporting axle being movable with respect to the pay off device whereby to maintain the contact of the paper roll with said pay off devices. 115

8. An autographic register comprising a casing having an opening, a paper support below the opening, manually operated devices for drawing the paper over the support, a plurality of paper roll supporting axles, and a single pay off device coacting with the several paper rolls mounted upon 120 125

said supporting axles to effect uniform pay off of the paper web therefrom irrespective of the relative size of the rolls.

9. An autographic register comprising a casing having an opening, a paper support below the opening, manually operated devices for drawing the paper over the support, a paper roll supporting axle, an endless belt paper pay off device positively actuated by said manually operated devices and arranged to engage a roll of paper mounted upon said supporting axle to pay off the paper as it is drawn over the paper support.
10. An autographic register comprising a casing having an opening, a paper support below the opening, manually operated devices for drawing the paper over the support, a paper roll supporting axle, a flexible paper pay off device to pay off the paper as it is drawn over the paper support, said paper feeding device normally contacting a roll of paper mounted upon said supporting axle, and guides for said flexible paper pay off device located adjacent the point of contact of said device with the paper roll.
11. An autographic register comprising a casing having an opening, a paper support below the opening, manually operated devices for drawing the paper over the support, a rotatable endless band device and vices for drawing the paper over the sup-

port, a paper roll supporting axle, a flexible paper pay off device to pay off the paper as it is drawn over the paper support, said paper pay off device normally contacting a roll of paper mounted upon said supporting axle, and guides for said flexible paper pay off device located adjacent the point of contact of said device with the paper roll, said guides constituting supports for the paper roll.

12. In an autographic register the combination of a casing having an opening and a paper support below the opening, a paper feeding device manually operated to engage and feed a strip of paper a predetermined amount at each actuation of the actuating device, and a co-acting endless band to rotate the rolls of paper to cause them to pay off the same amount of the paper as is fed above the paper support.

13. The combination with a casing having a paper support, a hand operable actuating shaft, and a feed roller adapted to engage a paper strip and feed it over the paper support, a rotatable endless band device and a paper roll supported on and rotated thereby, said rotatable endless band being operated from the actuating shaft.

In testimony whereof I affix my signature.
AUGUST A. WIMMERS.
